UNITED STATES PATENT OFFICE.

ROBERT R. RUST, OF NEW YORK, N. Y.

MANHOLE COVER.

Application filed April 1, 1919. Serial No. 296,620.

To all whom it may concern:

Be it known that I, ROBERT R. RUST, a citizen of the United States, residing in New York city, Queens County, New York, have invented new and useful Improvements in Manhole Covers, of which the following is a specification, reference being had to the accompanying drawings, in which—

Fig. 1 is plan of my improved cover; Fig. 2 is an enlarged central section thereof; Fig. 2^a is a detail showing the meeting faces of the inner cover and seat therefor; Fig. 3 is a section on lines 3—3 of Fig. 2; Fig. 4 is a plan of a modified form of my invention; Fig. 5 is an enlarged central section thereof; Fig. 6 is a section on lines 6—6 of Fig. 4; Fig. 7 is detail showing a socket 12 with the end of the lock-bar in position therein; and Fig. 8 is a detail showing a modification of the meeting faces of manhole and cover.

My invention relates to manhole covers and consists in the construction of a manhole and of a cover which is designed to fit tightly and accurately in the manhole to prevent the entrance of dirt and moisture thereinto, and also prevent tampering with wires, pipes and tubes where the manhole gives access to conduits, tunnels, etc. My invention also consists in the construction and arrangement of parts which I shall hereinafter describe and claim.

Referring to the drawings, 2 indicates the manhole frame, 3 the exterior cover and 4 the seat therefor.

The inner cover 5 has its periphery 6 preferably tapered at an angle of approximately 2° from the perpendicular, while the seat 7 on the manhole is preferably at an angle of 2½° from the perpendicular. The tapered surfaces 6 and 7 are preferably machined in order that true meeting surfaces may be obtained and a tight joint insured.

In Figs. 1, 2, 3, I have shown the cover 5 secured in position by means of a lock-bar 8. The end 9 of the lock-bar is inserted in a socket 10 of the frame, and the reduced end 11 is dropped into the socket 12 on the opposite side of the frame. The end of the saddle plate 13 is inserted beneath the lugs

of the socket 12 and forced down into position on top of the bar 8, with the staple 14 extending through the slot 15, in which position it may be secured by a padlock.

In Figs. 5, 6, 7, the lock-bar 8' is inserted into the sockets 10' and 12' from the side, and is secured in this position by passing the staple 14' through the slot 16 in the lug 17 on the cover.

In Fig. 8 I have shown a modification of the meeting faces of manhole and cover in which the meeting face 6' of the cover is machined at an angle of 2½°, while the face 7' of the manhole is machined at an angle of 2°.

The inner cover is equipped with lifting rings 18, to permit its easy removal.

By reason of the differential tapers between the meeting surfaces of the seat and cover, a line contact therebetween is obtained and a tight joint thereby secured. The lock-bar assists in causing the cover to settle firmly in its seat, and when it is in position and locked it holds the cover in place and prevents its removal without unlocking the bar.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. The combination of a manhole and a cover having cone-shaped metal meeting surfaces, the said surfaces being tapered, the taper of one of said surfaces being at a greater angle from the perpendicular than the taper on the other of said surfaces to insure a tight metal-to-metal joint therebetween.

2. The combination of a manhole and a cover therefor having cone-shaped metal meeting surfaces, the least diameter of the said manhole surface being less than the least diameter of the cover, the said meeting

surfaces being tapered, but the taper of the manhole surface being at a greater angle from the perpendicular than the cover surface so as to provide a tight metal to metal joint between manhole and cover.

3. The combination of a manhole and a cover having cone-shaped metal meeting surfaces, the said surfaces being arranged at

different angles, the angle of one of said surfaces from the perpendicular being 10 greater than that of the other of said surfaces to provide a line contact therebetween, and means for securing the cover in position upon the said manhole surface.

ROBERT R. RUST.
